WEB ASSEMBLING MEANS FOR PRINTING PRESSES

Edmund W. Dean, Battle Creek, Mich., assignor to Duplex Printing Press Company, Battle Creek, Mich., a corporation of Michigan

Application April 19, 1937, Serial No. 137,857

8 Claims. (Cl. 270—5)

This invention is an improvement in newspaper web printing presses of that type in which a multiple of web perfecting units are arranged in line with a folder unit, and provided with means whereby webs can be fed to each unit and the printed webs directed from the units to the folder.

Usually one of the press units is adapted to print a special page or pages, which ordinarily appear as page 1 in the completed paper and must be assembled with the product of some other particular unit. It is desirable to enable such special page or pages to be assembled with the product of any other unit, and mechanism for this purpose is disclosed in my copending application filed April 19, 1937, Serial No. 137,856, wherein adjustable web deflecting mechanism is employed at the side of the press. My present invention provides novel adjustable web deflecting mechanism above the press, whereby a web printed on one unit of the press, and bearing some special feature, can be assembled or associated with any other web printed on any other unit of the press instead of being confined as heretofore to that relative position in the final assembly of the webs in which it would ordinarily appear.

The web bearing the special featured page is usually arranged so that such page will appear as the title page, or page 1 of the finished paper, but at times it is desirable to divert such special feature page to some other portion of the finished product. Presses, of the type referred to, print newspapers consisting of a large number of pages ordinarily delivered in sections. It is frequently desired to have pages which have special features that differentiate them from the usual newspaper page (such as half-tone cuts, colors, or distinctive type) appear on the first page of any section of the paper, or it may be desired to have same appear on an inside page of any section of the paper.

The "unit" type of newspaper press comprises a number of perfecting units each capable of producing from four to eight perfected pages according to whether the plate cylinders are two-plate or four-plate wide; and if four-plate wide units are employed each unit has associated with it a group of angle bars to divert one longitudinal section of the web out of the straight line passage to the folder, and place it over or under the remaining straight running section, both sections being then directed to the folder. In a two-plate wide press the aforesaid angle bars are not required, but in a four-plate wide press such angle

bars are usually arranged near or over each printing unit. If such four-page wide newspaper press is operated at full capacity each perfecting unit will print eight pages, four on each longitudinal section of the web, and these may be run to and through the folder and delivered as separate eight-page papers; or the webs may be combined with the webs printed by other units and delivered in sections each containing more than eight pages up to the full page capacity of 10 the press.

My present invention provides novel means whereby the special pages produced on one unit may be assembled with the product of any other unit, as may be desired by the pressman or publisher. Such means includes novel web deflecting mechanism adjustably mounted above the units and guides whereby the web bearing the special pages may be assembled with any other web. To facilitate an understanding of the invention I will explain same in connection with a multi-unit newspaper press commonly known as a "unitubular" press in which the units employ single-page cylindric plates, but the invention is not limited to such type of press as will be readily understood by those familiar with the art.

To enable others to understand and use the invention I will explain the same with reference to the accompanying drawings, and will summarize in the claims the essentials of the invention, the novel features of construction, and novel combinations of parts, for which protection is desired.

In said drawings:—
Fig. 1 is a side elevation of my invention as adapted for use with a multi-unit printing press having four printing units, a folder, and web supply.

Fig. 2 is an enlarged top plan view of the web deflecting mechanism.

Fig. 3 is a transverse section on line 3—3, Fig. 2. The printing press shown comprises four perfecting units 1, 2, 3, 4, arranged in line with a folder 6 at one end, and a web supply at its other end. The webs W1, W2, W3, W4 are led from the rolls R1, R2, R3, R4 to their respective printing units, and from them to the folder 6.

In the press shown the unit 1 is adapted to special features on the web W1, and this web W1 may be deflected by my novel web deflecting mechanism and re-entered into the press between and assembled with any one of the webs W2, W3, W4, before it passes to the folder 6.

The press shown has the usual top ties 5a at 55

each side; and upon the ties are mounted longitudinally disposed bars 7 having short down-turned ends whereby they are spaced above the ties. Bars 7 are of sufficient length to extend 5 from the folder to and over the printing units 2, 3, 4.

Slidably mounted upon the bars 7 is a web deflecting frame consisting of side members 9 connected by cross-ties 9a. One member 9 carries 10 spaced depending brackets 9b that depend to a point somewhat below the ties 5a. In the upper ends of the brackets 9a is journaled a guide 10 and between the lower ends of the brackets 9b is journaled a guide 11. At the side of the frame, 15 towards the unit 1, is journaled a guide 12. Between the members 9a is mounted an angle bar 13 for directing the web to the guide 10.

Adjacent each end of bars 7 are bearings 7a for lead screws 7b having beveled gears 7c at 20 one end meshing with bevel gears 8c on a transverse shaft 8 journaled in bearings 8a on the tops of bars 7. The screws 7b extend through threaded bores in members 9, and by rotating screws 7b the web deflecting frame can be adjusted longitudinally of the press to any desired 25 position. The screws may be rotated manually by a crank 8d on shaft 8, or can be operated by power means if desired.

At the end of the members 7 adjacent unit 1 30 is a guide 14 over which is led the web W1 from press unit 1.

In the press frame below the ties 5a and disposed at the approximate height of the guide 11 are angle bars 15, 16, 17 supported between rods 35 15a, 16a, 17a which may be mounted in brackets 5b attached to ties 5a. Angle bar 15 is disposed between press units 2 and 3; bar 16 between units 3 and 4; and bar 17 between unit 4 and folder 6; and each of the bars are adapted to direct the 40 web from slide frame guide 11 towards the folder 6.

The webs W2, W3 and W4 from units 2, 3 and 4 may be led over their respective guides 2a, 3a, and 4a direct to folder 6 as usual. If the web 45 deflecting mechanism is not being used, the web W1 from unit 1 may also be led over guides 14 and 12, and directed (as web W1a, Fig. 1) over guide 1a at the outer end of bars 7, to the folder 6.

Assuming the web deflecting frame to be in the 50 position shown in the drawings (i. e., disposed between printing units 3 and 4) the web W1 may be directed over guides 14 and 12 to and under angle bar 13 of the slide frame, and deflected laterally (as web W1b, Figs. 1 and 2) to and 55 over guide 10, down under guide 11, over and under angle bar 16, and thereby deflected and directed towards the folder 6; the web W1b passing from angle bar 16 to and over guide rolls 1m, 1n disposed between the units 3 and 4, and thence passing to folder 6 assembled with the web W3.

If frame 9 was positioned between the units 2 and 3, the web W1 would issue from guide 11 of the slide frame and would pass over and under 60 angle bar 15, and over guides 1p, 1q, disposed between the webs W2, W3 and then pass (as web W1c, Fig. 1) over guide 1r to the folder 6 and assembled with web W2.

If frame 9 is positioned between unit 4 and 65 folder 6, the web W1 could be led from guide 11 of the slide frame over and under angle bar 11, under guide 1s, to folder 6, the web W1 passing as web W1d, Fig. 1, and being assembled with web W4.

The special printing unit may print a one-

page wide special feature in which case the web deflecting mechanism would not be needed in order to merely lead such a one-page wide web W1 into the folder as the outside first page sheet, but if the special sheets are to be assembled with other webs, or to be placed as inside sheets, then the sheet deflecting means is used. The special feature unit 1 is shown as that nearest the web supply, but some other unit might be made the special feature unit, in which case the web deflecting mechanism would be re-located or re-adjusted accordingly, as will be obvious to the pressman. In some such re-arrangement, if desired a guide 10x similar to guide 10 might be mounted on the slide frame 9 at the opposite 15 side of the press, as indicated in dotted lines in Fig. 2.

It might be necessary to reverse the angle bars 15, 16, 17 and the angle bar 13 so as to properly direct the diverted web if it is desired to turn 20 such web upsidedown in order to enable the special feature web to be inverted.

Obviously a greater or less number of printing units may be used, and by the use of appropriate slitters and guide rolls, as shown in my co-pending application the webs may be four-pages wide; the folder may be either straight run, or collecting and deliver the paper in sections or as a unit.

I claim:—

1. In a newspaper printing press having a plurality of printing units and a folder arranged in line; web deflecting means adjustable longitudinally of the press whereby a web from one unit may be diverted from its normal path and returned to the path of a web from another unit and associated therewith prior to folding thereof.

2. In a newspaper printing press having a plurality of printing units and a folder arranged in line; web deflecting means comprising a frame carrying an angle bar and guides adjustable longitudinally of the press, whereby a web from one unit may be diverted from its normal path and returned into the path of a web from another unit and associated therewith prior to folding thereof.

3. In a printing press having a plurality of printing units arranged in line, an angle bar above each unit, and a folder unit in line with the printing units; web deflecting means adjustable longitudinally of the press whereby a web from one unit may be diverted from its normal path and returned into the path of a web from another unit and associated therewith prior to folding thereof.

4. In a printing press having a plurality of printing units arranged in line, an angle bar above each unit, and a folder unit in line with the printing units; web deflecting means comprising a frame carrying an angle bar and guides, adjustable longitudinally of the press whereby a web from one unit may be diverted from its normal path and returned to the path of a web from another unit and associated therewith prior to folding thereof.

5. In a printing press having a plurality of printing units, an angle bar above each afore-said printing unit, a special printing unit in line with the other units, and a folder unit in line with the printing units; web deflecting means adjustable longitudinally of the printing units whereby a web printed by the special unit may be diverted from its normal path and returned into the path of a web from another unit and associated therewith prior to folding thereof.

6. In a printing press having a plurality of printing units, an angle bar above each aforesaid printing unit, a special printing unit in line with the other units, and a folder unit in line with the printing units; web deflecting means comprising a frame carrying an angle bar and guides adjustable longitudinally of the printing units whereby a web printed by the special unit may be diverted from its normal path and re-turned into the path of a web from another unit and associated therewith prior to folding thereof.
- 5 7. In a newspaper printing press, a plurality of perfecting units, a special printing unit, and a folder arranged in line, an angle bar above each 10 perfecting unit, and a web supply for each unit; a frame mounted above the units and carrying an angle bar and web guides, and means for
- 15

adjusting the frame longitudinally of the press whereby the web printed by the special unit may be deflected and associated with the web printed by any perfecting unit prior to folding thereof.

8. In a printing press having a plurality of perfecting units, a special printing unit, a folder arranged in line, a web supply and guides for directing webs from the supply to the several units and from the several units to the folder; angle bars above the perfecting units; a frame movable 10 longitudinally of the press above the units, an angle bar and guides on said frame, and means for adjusting said frame whereby a web printed by the special unit may be deflected and assembled with the web printed by any perfecting unit before 15 folding thereof.

EDMUND W. DEAN.
